GARMENT INSERT

Gertrude Nimetz, Rego Park, N. Y., assignor to
 G. H. and E. Freyberg, Inc., New York, N. Y.,
 a corporation of New York

Application December 22, 1945, Serial No. 637,001

6 Claims. (Cl. 223—71)

This invention relates to an insert for an infant's or child's dress or other analogous article of apparel such, for example, as rompers, to minimize creasing and rumpling thereof, particularly when on display on counters where they are subject to handling.

Present conventional practice for storing and shipping infants' and children's dresses and other analogous articles of apparel involves the use of a tissue paper insert. In some cases the upper portion of the garment is draped or folded and then pinned to maintain the desired folded shape and also retain the insert in position and impart an attractive appearance to the garment. In other cases the upper portion of the insert is simply pinned to the garment to retain it in position. Usually the insert is placed in position after the garment has been carefully ironed to impart an attractive appearance thereto. The tissue paper inserts used have generally been of a length extending from the top portion of the garment to a point terminating short of the bottom of the garment leaving the lower portion of the garment free of support. Such garments when placed in piles on store counters, as is common sales practice in many stores, rapidly become creased and rumpled due to handling; particularly is this the case in connection with the lower or skirt portion of infants' and children's dresses.

The use of cardboard inserts extending substantially the full length of the garment has the serious objection that it is difficult to pin or otherwise secure the insert in place. It is particularly difficult to drape the upper portion of the garment into the desired draped shape to give the garment an attractive appearance and thereafter pin it to the cardboard insert to maintain the desired draped shape and retain the insert in place, since the force required to cause the pins to pass through the cardboard insert is substantial with consequent injury to the hands of the personnel performing this operation; moreover this task is time consuming.

Among the objects of this invention is to provide a garment insert which can be readily pinned in place or about which the upper portion of the garment can be draped, if desired, and readily pinned into the desired draped shape requiring little time and labor so to do, which insert materially minimizes creasing and rumpling of children's dresses including the lower or skirt portions thereof.

Another object is to provide such garment insert of attractive appearance and having dual utility, namely, not only does it function as a gar-

ment insert to prevent creasing and rumpling, but also upon removal from the garment constitutes a child's toy or amusement device.

Another object is to provide such garment insert which is inexpensive to manufacture and hence the use of which does not greatly increase the cost of the garment.

Still another object is to provide a garment insert which facilitates folding of the garment along a definite and predetermined line of fold thereby simplifying packaging of the garment.

Other objects and advantages of this invention will be apparent from the following detailed description thereof.

In the preferred embodiment illustrated on the drawings the invention is shown incorporated in a dress insert and the present description will be confined to the present illustrated embodiment of the invention. It will be understood, however, that the novel features and improvements are susceptible to other applications such, for example, as inserts for rompers or other garments; particularly infants' and children's garments. Hence the scope of this invention is not confined to the embodiment herein described.

In the accompanying drawings illustrating one embodiment of this invention in which like reference characters refer to like parts,

Figure 1 is a plan view of a child's dress, the lower portion of which is broken away to show the insert embodying this invention;

Figure 2 is a fragmentary vertical section of a child's dress having the insert therein in a folded position;

Figure 3 is a plan view of the insert embodying this invention;

Figure 4 is a plan view of one of the cutouts after removal from the cardboard or lower portion of the insert embodying this invention; and

Figure 5 is a fragmentary vertical section taken in a plane passing through line 5—5 of Figure 3.

Referring to Figure 1 of the drawings 10 indicates a child's dress comprising an upper bodice portion 11 and lower skirt portion 12. Disposed within this dress is an insert to minimize creasing or rumpling thereof, which insert as shown in Figure 3 consists of a lower portion 13 of relatively stiff material such as cardboard or pasteboard and an upper portion 14 of material such as tissue paper having sufficient stiffness to reinforce the bodice portion of the dress to prevent or minimize rumpling and creasing thereof, yet sufficiently soft to be readily penetrated by a pin so that little or no force is required to pin the insert in place.

In the embodiment shown in the drawings the upper portion 14 consists of four plies of tissue paper 15, 16, 17 and 18 which are adhesively joined as at 19 to the lower portion 13. Instead of a 4-ply construction a single layer of relatively thick tissue paper like material or two or more plies of such material readily penetrated by pins but having sufficient stiffness to accomplish the desired purpose of preventing creasing of the garment may be employed. The upper portion in general is shaped to conform with the outline of the dress into which it is inserted and comprises a neck portion 20, shoulders 21, 22 and converging side edges 23, 24, which, as shown in Figure 1, conform with the shape of the bodice 11.

The lower portion 13 of the insert is preferably made of cardboard, pasteboard or analogous inexpensive fibrous or other material which when inserted in the dress prevents or minimizes creasing and wrinkling thereof. It is shaped to conform to the skirt portion of the dress and comprises diverging side edges 25, 26 and a lower curved edge 27 which may be scalloped or provided with other ornamental appearance, if desired.

In the embodiment of the invention shown in Figure 3 the lower portion 13 is provided with a series of toy cutouts arranged on the face thereof to impart an attractive appearance to the insert. As shown in Figure 3 the toy cutouts may comprise a doll simulating portion 28 either male or female and suitable apparel portions such as the dresses 29 and spron 30, each provided with foldable tab portions 31. As will be understood the toy cutouts when cut along their outlines produce a doll and dress or other apparel as shown in Figure 4, which dress, when associated with the doll and the tabs 31 are folded along lines 32, is retained in position on the doll to give it a dressed appearance.

It will be understood the representation of a doll and articles of apparel appearing in Figures 3 and 4 are merely for purposes of illustration and that any desired attractive appearing toy cutouts may be formed on the lower part of the insert to render it useful as a toy or game appealing to children.

The combination of an upper tissue paper portion 14 and a lower cardboard or relatively stiff portion 13 shaped to conform with the garment in which the insert is to be used not only minimizes creasing of the garment when placed in unfolded condition, but also facilitates the packaging of the garment in desired folded condition. The line of jointure 33 between the tissue paper portion 14 and the lower portion 13 defines a natural fold line for the insert. Hence, when the insert is placed in position, as shown in Figure 1, and secured in position by pins 34 which readily penetrate the fabric of the dress and the tissue paper, the dress when lifted by an operator automatically folds along line 33, i. e., the dress folds most easily along the line 33 of the insert, which line, it will be understood from Figure 4, occurs at the top of the skirt portion of the dress and the bottom of the bodice portion. It will be understood the inserts are manufactured in different sizes to accommodate different sizes of dresses. This feature of the insert embodying this invention facilitates packaging of the dresses in attractive folded appearance, if it is so desired to package the same.

When the dresses are placed on the counter in folded or unfolded condition with the insert therein the entire extent of the dress is pro-

tected by the insert against creasing and rumpling due to handling, the dress retaining its attractive ironed appearance for a much longer time, with consequent increase in sales appeal.

5 The sales appeal of dresses containing the inserts of this invention is further augmented by the utility of the insert as a toy or game when removed from the dress. Moreover, the use of the inserts does not add greatly to the cost of the dress, since the inserts are inexpensive to manufacture and can readily be pinned to the dress whether or not the dress is draped about the insert, or draped with the insert therein, since pins readily penetrate the upper tissue paper portion of the insert.

10 Since changes may be made without departing from the scope of the invention, it is intended that the above description should be interpreted in an illustrative and not in a limiting sense.

15 What is claimed is:

1. A garment insert to minimize creasing and rumpling of a textile garment, said insert comprising a flat upper portion of relatively thin material which is readily pinnable shaped to conform to the upper portion of the garment, and designed to minimize creasing and rumpling of the upper portion of the garment, and a flat lower portion of cardboard-like material shaped to conform to the shape of the lower portion of the garment, and said insert being of a length substantially equal to the length of the garment and adapted to be inserted in a garment in flattened condition to minimize creasing and rumpling thereof.

20 2. A child's dress insert comprising an upper tissue paper portion shaped to conform to the bodice portion of the dress, which tissue paper portion is readily pinned in desired position, and a lower cardboard portion having diverging side edges extending from the upper portion to conform in general to the shape of the skirt portion of the dress the length of said lower portion being substantially the same as the length of said skirt portion so that said dress insert minimizes creasing of substantially the entire extent of said dress.

25 3. A child's dress insert comprising an upper tissue paper portion shaped to conform to the bodice portion of the dress, which tissue paper portion is readily pinned in desired position, and a lower cardboard portion having diverging side edges extending from the upper portion to conform in general to the shape of the skirt portion of the dress, the length of said lower portion being substantially the same as the length of said skirt portion so that said dress insert minimizes creasing of substantially the entire extent of said dress, said lower portion having outlined on the face thereof toy cutouts.

30 4. A child's dress insert comprising an upper tissue paper portion shaped to conform to the bodice portion of the dress, which tissue paper portion is readily pinned in desired position, and a lower cardboard portion having diverging side edges extending from the upper portion to conform in general to the shape of the skirt portion of the dress, the length of said lower portion being substantially the same as the length of said skirt portion so that said dress insert minimizes creasing of substantially the entire extent of said dress, said lower portion having outlined on the face thereof doll and doll apparel cutouts.

35 5. A garment insert to minimize creasing and rumpling of a textile garment, said insert com-

prising a flat upper portion of tissue-paper-like material designed to minimize creasing and rumpling of the upper portion of the garment and a flat lower portion of cardboard-like material shaped to conform to the shape of the lower portion of the garment, said insert being of a length substantially equal to the length of the garment and adapted to be inserted in a garment in flattened condition to minimize creasing and rumpling thereof.

6. A child's dress insert comprising a flat up-

per tissue-paper-like portion shaped to conform to the bodice portion of the dress and a flat lower cardboard portion extending from the upper portion and shaped to conform to the skirt portion of the dress, the length of said lower portion being substantially the same as the length of said skirt portion, said insert being adapted to be inserted in a child's dress in flattened condition to minimize creasing and rumpling thereof.

GERTRUDE NIMETZ.
